Primary Examiner — Karen E Eldridge Powers(74) *Attorney, Agent, or Firm* — Margaret Polson; Oppedahl Patent Law Firm LLC(57) **CLAIM**

The ornamental design for an undergarment, as shown and described.

DESCRIPTION

FIG. 1 is a top plan view of my new design for an undergarment, the bottom plan view being identical thereto.

FIG. 2 is a side elevation view of the undergarment shown in FIG. 1, the opposite side elevation view being identical thereto.

FIG. 3 is a front elevation view of the undergarment shown in FIG. 1.

FIG. 4 is a back elevation view of the undergarment shown in FIG. 1.

FIG. 5 is a top plan view of the undergarment of FIGS. 1-4 shown in a second configuration, the bottom plan view being identical thereto.

FIG. 6 is a perspective view of the undergarment in the first configuration, shown on a wearer.

FIG. 7 is a perspective view of the undergarment in the first configuration, shown on a wearer.

FIG. 8 is a perspective view of the undergarment in the second configuration, shown on a wearer.

FIG. 9 is a perspective view of the undergarment in the first configuration, shown on a wearer.

FIG. 10 is a perspective view of the undergarment in the first configuration, shown on a wearer; and,

FIG. 11 is a perspective view of the undergarment in the second configuration, shown on a wearer.

The features shown in broken lines in the drawing depict environmental subject matter only and form no part of the claimed design.
